UNITED STATES PATENT OFFICE.

JOHN ELMER JONES, OF HAZLETON, PENNSYLVANIA.

COAL-PICKING TABLE.

No. 927,412.

Specification of Letters Patent.

Patented July 6, 1909.

Application filed December 29, 1908. Serial No. 469,852.

To all whom it may concern:

Be it known that I, JOHN ELMER JONES, a citizen of the United States of America, and residing in the city of Hazleton, in the county 5 of Luzerne and State of Pennsylvania, have invented a certain new and useful Improvement in Coal-Picking Tables, of which the following is a specification.

My invention relates to picking tables and 10 particularly to a chute or table for the hand picking of slate from coal, the object of my invention being to provide an improved device of this character as more fully explained below.

15 In the accompanying drawings, Figure 1 is a vertical section taken longitudinally through a picking table embodying my invention; and Fig. 2 is a plan of the same.

It is now customary after the coal has 20 come from the jigs, screens and automatic separators which are in general use at coal breakers, to feed the coal to a chute or traveling belt which carries the coal past hand pickers who are arranged upon or on each 25 side of the chute or belt and pick from the passing stream of coal such slate and other impurities as have not been eliminated in the automatic separator. Traveling belts are however, very expensive for this work 30 and while fairly satisfactory in certain respects are not in as common use as chutes. The latter are constructed of iron or steel, and are adjusted to the desired incline beneath a hopper which receives the coal from 35 the automatic separators or screens. When the incline has been adjusted, the chute remains stationary and the coal slides down by gravity at a speed which is of course governed principally by the incline at which 40 the chute is adjusted. These chutes are however unsatisfactory in operation since it is difficult to secure their adjustment to the proper angle, the surface of the chute varying from hour to hour in the smooth- 45 ness of its surface, (owing to oxidation over night) and it is a common sight to see the pickers either pulling the coal down the chute with the left hand while picking with the right, or on the contrary, holding back 50 with the right hand while picking with the left. It is obvious that the efficiency of the pickers is thus materially less than it would be were a steady even flow of coal past them supplied, thus enabling them to use both 55 hands at all times for picking. My present device aims to accomplish this end, while the

apparatus employed is of simple construction and operation and at the same time of increased efficiency in operation. It comprises an inclined table A pivoted at its lower 60 end upon standards B and subjected at its upper end to the action of a smoothly acting cam C, the term cam being used in a sense broad enough to cover an eccentric as shown. This cam may be mounted in bearings D carried by the standards E. A shoe F at the upper end of the table is provided for the cam to bear against; while the lower end of the table is made vertically adjustable to regulate the speed of the flow of coal. Any 65 suitable adjusting means may be employed, as for instance a threaded screw G with handle g, passing through a nut and plate H which rest on the slotted standards B and engaging the yoke I, which forms a bearing 70 for the pivoting spindle K carried in the brackets L on the lower end of the table.

As will be noted from the cross section Fig. 1, the bottom M of the table is not of uniform pitch from one end to the other, but 80 gradually increases in pitch toward the lower end. It is immaterial whether this change in pitch be obtained by a series of overlapping plates, the pitch of which is gradually increased, as shown in the drawing, or the 85 change in pitch takes the form of a parabolic curve, sharpest at the lower end of the table. The object of this construction of the table bottom is principally two fold. In the first place the pitch being less at the head of the 90 chute the coal which is delivered from the hopper in a more or less concentrated stream midway between the sides of the table has a chance to spread out into a comparatively evenly distributed shallow current of coal by 95 the time it reaches the pickers arranged farther down along the sides of the table and the slate and other impurities are thus not buried beneath the coal and missed by the pickers as is not infrequently the case with 100 the stationary chutes generally used. In the second place, the table being pivoted at the lower end the throw of the cam gradually decreases in effect from the upper to the lower end of the table and this must be compensated for by increasing the pitch in the manner described. Otherwise the coal backs up at the lower end of the table and obstructs the flow of the current.

It should be pointed out that the throw of 110 the cam is slight, for example about two inches on a twelve foot table, yet this has

proved very efficacious in practice for the purpose mentioned. Again it should be remarked that the cam employed is smooth and imparts an undulating motion to the upper end of the table. An eccentric is perhaps the ideal, but a smooth cam of moderate throw answers very well.

In operation the cam being rotated at a suitable speed the coal discharged upon the upper end of the table spreads out under the movement of the cam and flows in a steady stream past the pickers. If the flow is not at the desired speed the latter may be controlled by raising or lowering the lower end 15 of the table as explained.

It has been demonstrated in actual operation that the flow of coal past the pickers is much more uniform than in the chutes in common use and that in consequence the efficiency of the pickers is greatly increased 20 since the time and effort previously used in pulling down or holding back the coal may now be devoted exclusively to picking.

Modifications for the details of my construction, which do not depart from the scope of the invention will readily suggest themselves, and I do not limit myself to the precise structure shown.

I claim as my invention:

1. A hand picking table of the type described, having a smooth sliding surface for the unobstructed passage of the material to be inspected, said table being arranged on an incline and pivoted at its lower end, in combination with means to impart to the upper end of said table a smooth vertically reciprocating motion whereby a steady feed of the material down said table is obtained, substantially as described.

2. A picking table of the type described arranged on an incline and pivoted at its lower end, the bottom of said table being of varying pitch increasing toward the lower end, in combination with a smoothly acting cam bearing against the upper end of said table to impart to the same an undulating feeding motion, substantially as and for the purpose described.

In testimony whereof I have signed my name to this specification, in the presence of 50 two subscribing witnesses.

JOHN ELMER JONES.
